REFRIGERATING APPARATUS

Harry B. Hull, Dayton, Ohio, assignor, by mesne assignments, to Frigidaire Corporation, a corporation of Delaware

Application November 20, 1926, Serial No. 149,761
Renewed March 1, 1933

8 Claims. (Cl. 62—99)

This invention relates to cooling units for mechanical refrigerators, and more particularly to cooling units which are adapted to be installed in a refrigerator cabinet of the household type. 5 One of the objects of the present invention is to provide a cooling unit of simple and economical construction which will freeze or congeal substances quickly and also maintain the food compartment of the cabinet at the proper temperature.

10 Further objects and advantages of the present invention will be apparent from the following description, reference being had to the accompanying drawing wherein a preferred embodiment of one form of the present invention is clearly shown.

In the drawing:

Figs. 1 and 2 are front views partly in vertical section of refrigerator cabinets provided respectively with cooling units embodying two forms of the present invention; and

Fig. 3 is a sectional view taken on a line 3—3 of the cooling unit shown in Fig. 1.

Referring to the drawing, 20 designates a refrigerator cabinet having an L-shaped food compartment 21 separated from a cooling chamber 22 by an L-shaped partition 23. As indicated by the arrow 24 warm air passes from chamber 21 to chamber 22 through a flue 25, is cooled by the cooling unit 30 (to be described) and descends as indicated by the arrow 26 through a flue 27.

The cooling unit 30 comprises a closely wound pipe coil 31 or a coil of pipe having convolutions thereof arranged in contiguous relation to one another which is suspended from the top wall of the cabinet 20 by bracket members 32 and 33. The coil 31 is located within the cooling compartment 22 so as to be in contact with air circulating through the compartment as indicated by the arrows 24 and 26. The coil 31 provides a wall cooperating with the front and rear walls of the cooling chamber 22 to enclose a space 34 which is isolated from the circulating air in the cabinet by the coil 31 and therefore may be maintained at a lower temperature than the food compartment 21. The coil 31 encloses a coil 35 located within the space 34 and connected in series with the coil 31. It is apparent that the cooling unit provides what may be termed a freezing zone for quickly freezing or congealing a substance and provides what may be termed a cooling zone for the general cooling of the refrigerator. Air passing over coil 31 is cooled to the desired temperature for the refrigerator, not too cold for general refrigeration and the coil 35 being nested with-

in the coil 31 and thus protected from the effects of the circulating air, provides a freezing zone, the temperature of which may be maintained relatively low. The inlet end 36 of the coil 35 is connected with an expansion valve 37 which controls the flow of liquid refrigerant to the coil 35 from a refrigerant condensing apparatus connected to the expansion valve by a pipe 38. A pipe 39 connected with the outlet end of coil 31 conducts expanded refrigerant to the condensing machine. The expansion valve 37 is located preferably in the space between the coils 35 and 31 so that this valve and the pipe 38 will be maintained at a low temperature, and so that the valve will not take up room required by the air circuiting around the coil 31.

The coils 35 may be attached to and thermally connected with one or more metal sleeves 40, each adapted to receive a metal tray 41 for containing matter to be frozen.

In operation, liquefied refrigerant will enter the coil 35 and will begin to expand and thereby reduce the temperature of the space 34. Expansion of the refrigerant will continue in the coils 31 in order to reduce the temperature of the air circulating past these coils. During the course of operation frost will accumulate around the coil 35 and may even build up into contact with the interior of the coil 31. Owing to the relatively great area of coil 31 exposed to circulating air, accumulation of frost upon the outside of coil 31 will be relatively slow. It is apparent that during the idle period of operation of the refrigerating machine, the exterior of the coil 31 will be at least partially defrosted, while the frost will remain upon the coil 35 to maintain a desired low temperature within the freezing space during the idle period of the machine.

The form of invention shown in Fig. 2 is particularly adapted for refrigerator cabinets having only a rectangular space which may be separated into a food compartment 21a and a cooling chamber 22a by a detachable L-shaped partition 23a which stops short of the upper wall of the food compartment 21a to provide a flue space 25a and short of a side wall of the cabinet to provide a flue space 27a. The coils 31a and 35a are similar in function to the coils 31 and 35 of the first form described, but are elongated horizontally so as to occupy the minimum space vertically.

While the form of embodiment of the present invention as herein disclosed, constitutes a preferred form, it is to be understood that other forms might be adopted, all coming within the scope of the claims which follow.

What is claimed is as follows:

1. A cooling unit for mechanical refrigerators adapted to be placed in the path of medium to be cooled thereby, said cooling unit comprising heat exchange means in intimate contact with a refrigerant and with said medium to be cooled, said heat exchange means having a portion constructed and arranged to provide a freezing zone, and another portion comprising a plurality of duct means disposed in close juxtaposition and spaced from the portion providing the freezing zone to provide a substantially solid wall of heat exchange material for shielding the freezing zone from the action of the circulating medium.

15 2. A cooling unit for mechanical refrigerators adapted to be placed in the path of medium to be cooled thereby, said cooling unit comprising heat exchange means in intimate contact with a refrigerant and with said medium to be cooled, said heat exchange means having a portion constructed and arranged to provide a freezing zone, and another portion comprising a plurality of duct means disposed in close juxtaposition and spaced from the portion providing the freezing zone and surrounding the freezing zone to provide a substantially solid wall of heat exchange material for shielding the freezing zone from the action of the circulating medium.

25 3. A cooling unit for mechanical refrigerators adapted to be placed in the path of medium to be cooled thereby, said cooling unit comprising heat exchange means in intimate contact with a refrigerant and with said medium to be cooled, said heat exchange means having a portion constructed and arranged to provide a freezing zone, and another portion comprising a plurality of duct means disposed in close juxtaposition and spaced from the portion providing the freezing zone and on a plurality of sides of the freezing zone to provide a substantially solid wall of heat exchange material for shielding the freezing zone from the action of the circulating medium.

45 4. A cooling unit for a refrigerating apparatus adapted to be placed in the path of medium to be cooled thereby, said cooling unit comprising heat exchange means in intimate contact with a refrigerant and with said medium to be cooled, said heat exchange means including a portion constructed and arranged to provide a freezing zone, and other contiguously arranged portions forming refrigerant conveying duct means and being spaced from the portion providing the freezing zone to provide a substantially solid wall of heat exchange material for shielding the freezing zone from the action of the circulating medium.

55 5. A cooling unit for a refrigerating apparatus adapted to be placed in the path of medium to

be cooled thereby, said cooling unit comprising heat exchange means in intimate contact with a refrigerant and with said medium to be cooled, said heat exchange means including a portion constructed and arranged to provide a freezing zone, and other contiguously arranged portions forming refrigerant conveying duct means and being spaced from the portion providing the freezing zone and on a plurality of sides of the freezing zone to provide a substantially solid wall of heat exchange material for shielding the freezing zone from the action of the circulating medium.

60 6. A cooling unit for a refrigerating apparatus adapted to be placed in the path of medium to be cooled thereby, said cooling unit comprising heat exchange means in intimate contact with a refrigerant and with said medium to be cooled, said heat exchange means including a portion constructed and arranged to provide a freezing zone, and other contiguously arranged portions forming refrigerant conveying duct means and being spaced from the portion providing the freezing zone and surrounding the freezing zone to provide a substantially solid wall of heat exchange material for shielding the freezing zone from the action of the circulating medium.

65 7. A cooling unit for a refrigerating apparatus adapted to be placed in the path of medium to be cooled thereby, said cooling unit comprising heat exchange means in intimate contact with a refrigerant and with said medium to be cooled, said heat exchange means including a portion forming refrigerant conveying means constructed and arranged to provide a sharp freezing receptacle support, and other contiguously arranged portions forming refrigerant conveying means and being spaced from the portion providing the sharp freezing support to provide a substantially solid wall of heat exchange material for shielding the freezing support from the action of the circulating medium.

70 8. A cooling unit for a refrigerating apparatus adapted to be placed in the path of medium to be cooled thereby, said cooling unit comprising heat exchange means in intimate contact with a refrigerant and with said medium to be cooled, said heat exchange means including a portion forming refrigerant conveying means constructed and arranged to provide a sharp freezing zone, and other contiguously arranged portions forming refrigerant conveying means and being spaced substantially concentrically from the portion providing the sharp freezing zone to provide a substantially solid wall of heat exchange material for shielding the freezing zone from the action of the circulating medium.
